UNITED STATES PATENT OFFICE

JOSEPH H. ADDLER, OF BROOKLYN, NEW YORK, ASSIGNOR TO PULLCLEAN MANUFACTURING CORPORATION, OF BRIDGEPORT, CONNECTICUT, A CORPORATION OF DELAWARE

TOWEL CABINET

Application filed September 23, 1930. Serial No. 483,786.

This invention relates to towel cabinets of the type adapted to contain a so-called "continuous" towel, that is, a long length of towel, usually in roll form, which is adapted to be drawn outwardly through an opening in the cabinet in suitable predetermined lengths for drying purposes. This type of cabinet is usually provided with a roller mounted therein in position to be engaged and rotated by 5 the towel as the latter is withdrawn from the cabinet, the said roller being effective, by the alternate stopping and releasing of the same, to control the feed of the engaged towel from the cabinet.

15 One means for effecting such stopping and releasing of the feed controlling roller, as disclosed in my pending application, Serial No. 449,138, comprises a stop member, and a slidably mounted bolt carried by the roller 20 in a manner to be projected at one end from its support during rotation of the roller into position for engagement with said stop member, to thereby stop rotation of the roller and the consequent feeding or withdrawal of the 25 towel, and the said stop member being operative to thereafter shift the bolt to stop releasing position for permitting further rotation of the roller and the consequent further feeding or withdrawal of the towel.

30 The bolt of my aforesaid application is slidably mounted in a transversely arranged bore or opening in a block fixedly attached to one end of the feed roller for rotation therewith, whereby said bolt will slide outwardly from its supporting block under the action of gravity during rotation of the roller so as to project one end thereof into position for stopping engagement with the stop device. It sometimes happens however that 35

40 the bolt becomes stuck in its bore and fails to gravitate outwardly therefrom to its operative stop engaging position. Because of this, it has been the object of my present invention to provide a simple and efficient 45 means whereby the bolt, following its release from engagement with the stop device, will be positively returned to its projecting stop engaging position. Such means, constituting my present invention, is illustrated 50 in the accompanying drawings, in which:—

Fig. 1 is an end elevation of a cabinet equipped with the invention, with the outer casing in section and with the parts in roller stopping position.

Fig. 2 is a front view of that part of the 55 cabinet containing the roller stopping and releasing mechanism, with the front wall of the casing partly broken away.

Fig. 3 is an enlarged sectional detail of the roller stopping and releasing mechanism 60 with the parts in roller stopping position as in Fig. 1.

Fig. 4 is a similar view but with the bolt 65 in its released or inoperative position as effected by the stop device, which latter in effecting such operation serves also as a stop releasing device.

Fig. 5 is a similar view but with the roller further rotated and showing the bolt partially projected at its stopping end by the 70 engagement of an inclined or cam surface on its opposite end with the stop device.

Fig. 6 is another similar view with the roller further rotated and showing the bolt 75 in its fully projected position.

Fig. 7 is a central vertical section through the bolt carrying disk and adjacent sprocket on the end of the feed roller spindle, the section being taken on the line 7—7 of Fig. 3.

The cabinet, which may be of any desired 80 construction or design, is here shown as comprising an outer casing formed in two sections 2 and 3, the front section 3 being hinged at one of its vertical edges to the rear section 2, as at 4, whereby the casing may be opened 85 to permit of ready access to the interior thereof.

Located within the casing adjacent its opposite ends are a pair of frame or bracket plates for the support of certain parts of the 90 towel controlling mechanism to be presently described. Only one of these bracket plates, indicated at 5, is here shown, the same being secured in position by suitable fastening means, such as the bolts 6. The opposite 95 bracket plate (not shown) is of like construction and similarly fastened in position.

Carried by these bracket plates is a shelf 7 upon which is supported the roll of clean 100 towelling, indicated at 7. When so support-

ed, the leading end of the towel is led from the front side of the roller up and over a guide 8, from thence downwardly and partially around a feed roller 9, suitably journaled in the end brackets, and from thence forwardly through an opening 10 in the front wall of the casing to and over a guide roller 11, which latter is journaled in extensions of the bracket plates projected through the opening in the casing to support the roller 11 at the front side thereof as shown. From this guide roller the towel depends in loop form, as at 12, in convenient position for use; the towel at the rear side of the loop passing backwardly through the opening in the casing to a usual form of take-up or rewinding device comprising a pair of rollers 13 and 14, between which the towel is passed, the roller 12 being operative to pull the engaged towel into the cabinet and rewind it upon the roller 13. The roller 12 is operated in this way from the feed roller 9 when the latter is rotated by the frictional engagement therewith of the towel upon the withdrawal of the latter from the cabinet, the connection between the rollers being the usual chain and sprocket connection employed in these cabinets, such as the sprockets 15 and 16 rigidly attached to the respective rollers and engaged by the connecting chain 17.

As hereinbefore referred to, the means comprising my present invention is adapted for controlling the feed or delivery of the clean towel whereby its withdrawal from the cabinet will be in predetermined lengths. This is accomplished by the provision of means for automatically stopping the roller 9 once upon each rotation thereof and thereby stopping the outward feeding or withdrawal of the towel; it being understood that the friction between the towel and the roller is such as to prevent movement of the towel independently of the roller under ordinary pulling strains such as exerted in the normal use of the cabinet.

The means for stopping rotation of the roller 9 as referred to, comprises, in the form of the invention here shown, a bolt 20 slidably mounted in a transverse bore 21 formed in a housing block or disk 22 fixedly mounted on the squared end 23 of the spindle 24 which carries the roller 9; this bolt 20 being freely slidable in the bore 21 for movement transversely of the roller and being limited in its sliding movement by the engagement of the spindle end 23 with the end walls of an elongated groove 25 in the upper wall of the bolt, as best shown in Figs. 3 and 4. As a convenient means for placing the bolt in its bore 21 during the assembling of the parts, the disk 22 containing the bore is provided with an end cap 26 at one side of said bore which is removably held in position by suitable fastening means, such as screws 27.

When a length of towel is drawn outward-

ly from the cabinet, thereby causing rotation of the engaged roller 9, the bolt 20 will be moved in its bore 21 in the disk 22, by means to be hereinafter described, so as to project one end thereof, indicated at *a*, beyond the disk, as shown in Fig. 6. During continued rotation of the roller, the said projecting end of the bolt is brought into contact with the under face of a stop device 30, as shown in Figs. 1 and 3, and so stops rotation of the roller and thereby further withdrawal of the engaged towel. Subsequently, to obtain another length of towel, the bolt is released by the stop to permit another rotation of the roller. For effecting such release of the bolt, the stop device 30, as here shown, is in the form of a push-button slidably mounted for horizontal movement in a housing block 31 on the inner wall of the casing, with its head 32 at the outer side of the casing for convenient engagement by the user, and with its inner or end face adapted for pressing engagement against an end face 33 of the bolt 20, which end face 33 is brought to a position opposite the end of the stop device upon the engagement with the latter of the projecting end of the bolt as shown in Figs. 1 and 3. By pressing inwardly upon the stop device at this time, it acts to move the bolt 20 backward into its bore in the disk 22, as shown in Fig. 4, following which the stop device, upon being released by the user, will be automatically returned by a spring 35 to its normal position, as shown in Figs. 1, 3, 5 and 6, and thereby released from stopping engagement with the roller and its bolt 20. Thereafter the roller is free to make another rotation.

The cooperation of the bolt 20 and stop device 30 as thus far described is the same as that of my aforesaid application. In the latter, however, the bolt is projected only at one end thereof from the disk 22 and it does this under the action of gravity. In the present case and in accordance with my invention, the bolt is made of such length that when it is moved to stop releasing position by the inward pressure of the push-button 30, as shown in Fig. 4, its rear end *b* is thereby caused to project slightly beyond the adjacent side of the block 22 and in position for subsequent engagement with the stop device. This rear end of the bolt is provided with an inclined or cam surface 40 which, when brought into wiping engagement with the stop device during rotation of the roller, as shown in Fig. 5, serves to positively move the bolt in an endwise direction in its bore 21 to project its opposite end *a* into position, as shown in Fig. 6, for subsequent engagement with the stop device as shown in Fig. 3. In this way, it is positively assured that the bolt will be in stop engaging position at each rotation of the roller 9; the movement of the bolt under the action of the push-button to project its cam end into operative position

beyond the periphery of the disk 22 as shown in Fig. 4 being a positive one, the movement of the bolt in the opposite direction under the wiping engagement of its cam end with the stop to project its estopping end into operative position beyond the periphery of the disk 22 as shown in Fig. 6, also being a positive one.

What I claim is:

1. In a towel cabinet, the combination of a towel feed-controlling roller, a stop member, and a slidably mounted bolt carried by the roller movable in its support to alternately project its opposite ends into position for engagement with the stop member, one end of the bolt when in engagement with the stop member being effective to stop rotation of the roller and the other end having a cam surface for wiping engagement with the stop member during rotation of the roller to effect a positive endwise movement of the bolt to project its opposite end into stop engaging position.

2. In a towel cabinet, the combination of a towel feed-controlling roller, a stop member, a slidably mounted bolt carried by the roller movable in its support to alternately project its opposite ends into position for engagement with the stop member, one end of the bolt when in engagement with the stop member being effective to stop rotation of the roller and the other end having a cam surface for wiping engagement with the stop member during rotation of the roller to effect a positive endwise movement of the bolt to project its opposite end into stop engaging position, and means for moving the bolt to stop releasing position.

3. In a towel cabinet, the combination of a towel feed-controlling roller, a stop member, and a slidably mounted bolt carried by the roller movable in its support to alternately project its opposite ends into position for engagement with the stop member, one end of the bolt when in engagement with the stop member being effective to stop rotation of the roller and the other end having a cam surface for wiping engagement with the stop member during rotation of the roller to effect a positive endwise movement of the bolt to project its opposite end into stop engaging position, said stop member being operative to effect release of the bolt therefrom.

4. In a towel cabinet, the combination of a towel feed-controlling roller having a part thereof provided with a transversely arranged opening, a stop member, and a bolt slidably mounted in said opening of the roller for movement therein to alternately project its opposite ends into position for engagement with the stop member, one end of the bolt when in engagement with the stop member being effective to stop rotation of the roller and the other end having a cam

surface for wiping engagement with the stop member during rotation of the roller to effect a positive endwise movement of the bolt to project its opposite end into stop engaging position.

5. In a towel cabinet, the combination of a towel feed-controlling roller having a part thereof provided with a transversely arranged opening, a stop member, a bolt slidably mounted in said opening of the roller for movement therein to alternately project its opposite ends into position for engagement with the stop member, one end of the bolt when in engagement with the stop member being effective to stop rotation of the roller and the other end having a cam surface for wiping engagement with the stop member during rotation of the roller to effect a positive endwise movement of the bolt to project its opposite end into stop engaging position, and a push-button operative to move the bolt endwise in its said opening in the roller to release its stopping end from the stop member and at the same time project its opposite end into position for subsequent engagement with said stop member.

In testimony whereof I affix my signature:

JOSEPH H. ADDLER.
